UNITED STATES PATENT OFFICE.

CHARLES P. SKUBLIN, OF CHICAGO, ILLINOIS.

LOCK.

Application filed March 6, 1922. Serial No. 541,434.

To all whom it may concern:

Be it known that I, CHARLES P. SKUBLIN, citizen of Russia, residing at Chicago, county of Cook, State of Illinois, have invented a certain new and useful Improvement in Locks, and declare the following to be a full, clear, and exact description of the same, such as will enable others skilled in the art to which it pertains to make and use the same, reference being had to the accompanying drawings, which form a part of this specification.

My invention relates to an improvement in locks shown in the accompanying drawings and more particularly pointed out in the following specification and claims.

The primary object of the present invention is an improvement upon the lock shown and described in an application for Letters Patent filed by me June 2, 1921, Serial No. 474,340.

To this end one object of the invention consists in providing means whereby the lock cannot be "picked" by forcing its body portion—either by a blow or other means—to impinge upon the floating tumblers housed therein to prevent their freedom of action, whereby they may be individually forced to a position in which the peripheral grooves of the floating tumblers may be made to register with the arc-shaped slots in the fixed disc through which the tumblers project and rock in unlocking the swinging latch. The means employed to prevent tampering with the floating tumblers consists in providing each tumbler with a central movable stem on which is sleeved a spring bearing at one end against the floating tumbler and at the other end against an enlarged head at the end of the stem;—the springs serving under normal conditions to shift the tumblers upon the thrust of the stems by the application of a properly constructed key having a plurality of pins of different height respectively adapted to simultaneously give the several tumblers the necessary predetermined movement required to align their peripheral grooves with the arc-shaped slots in the fixed disc. In the event however of the free movement of the floating tumblers being restricted in the manner previously indicated any pressure applied to the enlarged head will force the stem through its tumbler without changing the position of the latter, thereby preventing "picking" the lock through the indi-

vidual operation of the several movable stems.

With the foregoing and other objects in view which will appear as the description proceeds, the invention further resides in the combination and arrangement of parts and in the details of construction herein-after described and claimed, it being understood that changes may be made in the precise embodiment disclosed without departing from the spirit of the same.

In the drawings accompanying this specification:

Figure 1 is a cross-sectional view through the lock showing the door and door casing in cross-section; the floating lock tumblers being in their initial position.

Figure 2 is a similar sectional view showing the key inserted in the lock;—the floating tumblers being shifted thereby to a position in which the latch may be actuated to either lock or unlock the door.

Figure 3 is a sectional view through the lock taken on or about line 3—3 of Figure 2, showing a fragment of the door and door casing.

Figure 4 is a perspective view of the lock housing, with a portion broken away to disclose an internal rib divided to receive the projecting lugs of a disc having arc-shaped slots through which extend a plurality of floating tumblers.

Figure 5 is a front elevation of the lock housing indicating a fragment of the door and door jamb, and in dotted lines the barrel of the lock housing, and also the latch engaging the socket member of the door jamb, and withdrawn therefrom.

Figure 6 is a perspective view of the key for simultaneously shifting the several tumblers.

Figure 7 is a cross-sectional view through the oscillating casting, bored to receive the floating tumblers, showing the peripheral groove into which pins project from the housing to secure it against dislodgment while permitting oscillation therein.

Referring now to the letters of reference placed upon the drawings:

A, denotes a main housing having a face plate A' provided with apertures A² to receive screws for securing it to a door. A³ is a divided internal annular rib integral with the wall of the housing. B, denotes a disc having lugs B' adapted to project between the ends of the divided rib A³ of the main

housing, to secure the disc against rotation. C, indicates an oscillating casting having a stem C' projecting through a central aperture in the disc B. D, is a rocking latch, pinned to the stem C' adapted to enter a socket member C² in door jamb. A⁴ are pins projecting into a peripheral groove C³ in the casting C, to secure the latter against dislodgment while permitting it to oscillate within the housing. E, denotes a plurality of floating tumblers projecting through the spaced apertures B², B², in the disc, and B³ is a relatively narrow arc-shaped slot connecting the apertures B², B² together. E' are peripheral grooves in the floating tumblers to permit the tumblers to pass through the narrow arc-shaped slot B³ between the apertures B², B², whereby the casting C may rock the latch bar D from a "locked" position to an "unlocked" position, or vice versa. F, are slidable stems respectively projecting through each of the floating tumblers provided with enlarged heads F' to receive the thrust of a spring G projecting from a socket in the end of each of the floating tumblers. H are springs also bearing upon the enlarged head of the movable stems and against a shoulder formed by counterboring the oscillating casting which serve to return the stems to their initial position when shifted by the key. I, denotes a nut secured to the projecting end of each of said stems overlapping the end of the floating tumblers to secure the latter against dislodgment. K, is a cap plate covering the face of the oscillating casting secured to the latter by pins K' projecting through the flange of the cap into holes bored into the body of the casting. K² are apertures in the cap plate to receive a plurality of pins L of relatively different length projecting from the key L' to operate the lock that its latch D may engage the plate M, of the door casing.

Having indicated the several parts by reference letters the construction and operation of the device will be readily understood:

When it is desired to actuate the swinging latch the key L' is applied (see Figure 2) so that its pins L, of varying length bear upon the enlarged heads F' of the slideable stems, respectively projecting through the several floating tumblers. The pressure of the pins against the enlarged heads of the stems serves to shift the latter together with the floating tumblers from the position shown in Figure 1 to that indicated in Figure 2 in which the peripheral grooves of the floating tumblers register with the arc-shaped slots between the apertures B², B² in the disc. The oscillating casting C and its swinging latch D, may now be rocked from an unlocked position to a locked position or vice versa.

In the event of an unauthorized person

attempting to individually adjust the floating tumblers to register with the arc-shaped slots in the stationary disc, by distorting the oscillating casting in which they are housed either by a blow of a hammer or other means, so that the tumblers may be held by friction against the wall of the casting when individually moved to secure registration with the arc-shaped slots,—it will be found that the pressure applied to the enlarged heads of the slideable stems F, will cause the latter to slide through the tumblers without changing the position of the tumblers,—(see dotted lines in Figure 1) the pressure of the springs H not being sufficient to force the tumblers to move with the stems as when operated under normal conditions.

Having thus described my invention what I claim is:

1. In a lock; a housing; a disc secured against rotation within the housing, provided with a plurality of arc-shaped slots, the ends of each slot terminating in an enlarged bore open thereto; an oscillating casting sleeved within the housing having a spindle projecting through a central bore in the disc; a swinging latch secured to the spindle to engage a locking member; a plurality of floating tumblers housed in bores in the oscillating casting and adapted to extend through the bores in the arc-shaped slots, having peripheral grooves adapted to register with the arc-shaped passage between said bores of the disc; a slideable stem extending centrally through each of the floating tumblers; a cap plate secured to the oscillating casting provided with a plurality of apertures to receive the projecting lugs of an operating key; springs mounted upon the slideable stems adapted to bear against the tumbler whereby upon applying pressure to the stems the tumblers will be shifted a corresponding degree and an operating key provided with a plurality of projecting lugs adapted to simultaneously bear upon the ends of the several slideable stems, whereby the floating tumblers may be adjusted that their peripheral grooves may register with the arc-shaped slots in the disc.

2. In a lock; a housing; a disc secured against rotation within the housing provided with a plurality of arc-shaped slots, each arc-shaped slot terminating in its ends in an enlarged bore opening into the slot; an oscillating casting sleeved within the housing having a spindle projecting through a central bore in the disc; a latch secured to the spindle; a plurality of floating tumblers housed in bores in the oscillating casting, having peripheral grooves adapted to register with the arc-shaped slots of the disc; a slideable stem extending centrally through each of the floating tumblers fitted with an enlarged head; a cap

- plate secured to the oscillating casting provided with a plurality of apertures to receive the projecting lugs of an operating key; springs mounted upon the slideable stems adapted to bear against the enlarged head of the stem and against the tumblers and springs surrounding said last named springs housed in counterbores in the oscillating casting adapted to bear against the enlarged head of the stems, whereby the stems may be returned to their initial position following the adjustment of the floating tumblers that the latter may register with the arc-shaped slots in the disc.
3. In a lock; a housing; a disc secured against rotation within the housing, provided with a plurality of arc-shaped slots having enlarged bores in each end of the slot; an oscillating casting sleeved within the housing having a spindle projecting through a central bore in the disc; a swinging latch bar secured to the spindle; means for securing the oscillating casting against displacement; a plurality of floating tumblers housed in bores formed in the oscillating casting, said floating tumblers having peripheral grooves adapted to register with the arc-shaped slots of the disc; a slideable stem extending centrally through each of the tumblers fitted with an enlarged head; nuts fitted to the end of the projecting stems overlapping the tumblers; a cap plate secured to the oscillating casting provided with a plurality of apertures adapted to receive the projecting lugs of an operating key; springs mounted upon the slideable stems adapted to bear against the enlarged head of the stem and against the tumblers; springs surrounding said last named springs housed in the counterbores in the oscillating casting, adapted to bear against the enlarged head of the stems, and an operating key having a plurality of projecting lugs of relatively different length adapted to project through the apertures in the cap plate, whereby they may bear upon the enlarged heads of the slideable stems to simultaneously adjust the floating tumblers.
4. In a lock; a housing having a divided internal rib; a disc provided with lugs extending between the divided rib, whereby the disc may be secured against rotation, said disc provided with a plurality of arc-shaped slots terminating at each end in an enlarged bore; an oscillating casting sleeved within the housing, having a spindle projecting through a central bore in the disc;
- a latch bar secured to the spindle; a plurality of floating tumblers housed in bores 60 in the oscillating casting adapted to project through the enlarged bore in each of the slots, said floating tumblers provided with peripheral grooves adapted to register with the relatively narrow arc-shaped slots connecting the bores in the disc; a slideable stem extending centrally through each of the tumblers; a cap plate fitted to the oscillating casting provided with a plurality of apertures, and a key having projecting lugs 70 adapted to extend through said apertures in the cap plate to act upon the stems, whereby the tumblers may be adjusted.
5. In a lock; a housing; a disc secured against rotation within the housing, provided with a plurality of arc-shaped slots having enlarged bores in each end of the slot; an oscillating casting sleeved within the housing having a spindle projecting through a central bore in the disc, said casting having a peripheral groove; pins extending from the housing into the peripheral groove of the oscillating casting; a swinging latch bar secured to the spindle of the oscillating casting; a plurality of 80 floating tumblers housed in bores formed in the oscillating casting, said floating tumblers having peripheral grooves adapted to register with the arc-shaped slots of the disc; a slideable stem extending centrally 85 through each of the tumblers fitted with an enlarged head; nuts fitted to the end of the projecting stem overlapping the tumblers; a cap plate secured to the oscillating casting provided with a plurality of apertures 90 adapted to receive the projecting lugs of an operating key; springs mounted upon the slideable stems adapted to bear against the enlarged head of the stem and against the tumblers; springs surrounding said last 95 named springs housed in the counterbores in the oscillating casting, adapted to bear against the enlarged head of the stems, and an operating key having a plurality of projecting lugs of relatively different length 100 adapted to project through the apertures in the cap plate, whereby they may bear upon the enlarged heads of the slideable stem to simultaneously adjust the floating tumblers.
- In testimony whereof, I sign this specification in the presence of two witnesses.
- CHARLES P. SKUBLIN.
